[57] CLAIM

The ornamental design for a lawn fertilizer feeder, as shown.

DESCRIPTION

FIG. 1 is a perspective view of a lawn fertilizer feeder showing our new design;

FIG. 2 is a top plan view thereof;

FIG. 3 is a side elevational view thereof, the opposite side being a mirror image of the side shown;

FIG. 4 is a front elevational view thereof; and

FIG. 5 is a rear elevational view thereof.

Fig. 2.
